Des. 236,589
Patented Sept. 2, 1975

236,589

GEOGRAPHICAL CLOCK

Seiji Toyoshima, Osaka, Japan, assignor to Sharp
Kabushiki Kaisha, Osaka, Japan

Filed June 7, 1973, Ser. No. 367,782

Claims priority, application Japan July 28, 1972

Term of patent 14 years

Int. Cl. D10—01

U.S. Cl. D10—10

FIG. 1

FIG. 2

FIG. 3

FIG. 4

FIG. 5

FIG. 6

FIG. 1 is a left front perspective view of a geographical clock showing my new design, the top covering the control buttons shown in the open position;

FIG. 2 is a top plan view thereof with the top which covers the control buttons being in the closed position;

FIG. 3 is a front elevational view of FIG. 2;

FIG. 4 is a rear elevational view of FIG. 3;

FIG. 5 is a left side elevational view of FIG. 3, the right side being a mirror image thereof; and

FIG. 6 is a bottom plan view of FIG. 3.

I claim:

The ornamental design for a geographical clock, as shown.
